UNITED STATES PATENT OFFICE.

VINCENT CHWALKOWSKI, OF NEWARK, NEW JERSEY.

DESIGN FOR A HEATER.

Application filed June 16, 1922. Serial No. 2,702. Term of patent 3½ years.

To all whom it may concern:

Be it known that I, VINCENT CHWALKOWSKI, a citizen of Poland, and residing at Newark, county of Essex, and State of New Jersey, have invented a new, original, and ornamental Design for Heaters, of which the following is a specification, reference being had to the accompanying drawing, forming part thereof.

I claim:

The ornamental design for a heater, as shown.

VINCENT CHWALKOWSKI.
